UNITED STATES PATENT OFFICE.

MAX FRIEDRICH GUTERMUTH, OF DARMSTADT, GERMANY.

CLACK OR FLAP VALVE.

949,070.

Specification of Letters Patent. Patented Feb. 15, 1910.

Application filed September 27, 1907. Serial No. 394,892.

To all whom it may concern:

Be it known that I, MAX F. GUTERMUTH, a subject of the Emperor of Germany, residing at Darmstadt, Germany, have invented certain new and useful Improvements in Clack or Flap Valves, of which the following is a specification.

Clack or flap valves, which consist of a flat closing plate with spring coils connected therewith in spite of their great advantages frequently have the drawback, more particularly in the case of very broad flaps, that the opening movement, especially in rapid working, does not take place uniformly over the entire width, but that oscillations and vibrations arise.

In order to avoid this drawback, the object of the present invention is to stiffen and guide the spring coils by suitable means.

For this object the coils, with the exception of the first which is directly connected to the flat plate, are made shorter than the actual seat plate, and in the free spaces thereby formed at both ends, guide rings are fixed on the spindle on which the innermost coil is mounted. As these guide rings are also wholly or partially inclosed by the first broad coil, in the opening movement a suitable guidance for the flap is obtained by this means, so that, more particularly in the case of very wide flaps, oscillations and vibrations, facilitated by the easily movable spring coils, are avoided. By the shortening of the spring coils, the advantage is also obtained that the spring resistance and consequently the resistance of the flap (to the passage of the fluid) is diminished, so that it is possible to select thicker plates and nevertheless by a suitable diminution of the length of the coil to reduce the strength of the spring to the desired degree.

The improved clack or flap valve is shown in one form of construction in the accompanying drawings, in which:—

Figure 1 is a section on the line A—A, and Fig. 2 a section on the line B—B of Fig. 3, Fig. 3 is a plan view of the valve, Fig. 4 shows a development or projection of the plate, and Fig. 5 is a plan view of a plate having simple circular perforations instead of elongated ones.

The first spring coil b, as shown more particularly in the section on the line B, B, is connected along its full length with the flat closing plate a. The succeeding coils c on

the other hand are made considerably shorter than the entire width of the flap, so that free spaces are formed on both sides of the flap. In these free spaces two guide rings e are then passed from the side on to the spindle d which carries the innermost spring coil which is secured to the spindle. These guide rings entirely fill the said free spaces in such a way that internally they encounter the spring coils, but externally do not project beyond the width of the flap. Now as the first coil b, as may be seen in the drawings, wholly or in any case partially incloses both guide rings e, the guide rings prevent the valve flap being lifted unevenly in the opening movement, and any fluttering, vibrating and oscillating of the flap such as may take place in consequence of the flexibility of the spring coils, more particularly in the case of very wide flaps, is avoided. At the same time, as already mentioned, by the shortening of the spring coils, the spring resistance of the valve and therefore the resistance to the passage of the fluid, is reduced. Consequently the thickness of the plate a may be made greater than hitherto and the same thickness of plate may also be used for the coil part, while by this invention the length of the coil may be so far diminished that the spring pressure is reduced to the desired extent. On the other hand, the coils must not be shortened too much in order that in the case of large sized flaps the uniform action of the spring pressure over the entire width of the flap shall not be affected. Now in order in spite of that to diminish the resistance of the spring to the necessary extent in the case of thicker plates, the coil part of the plate may be provided with notches, perforations and the like.

Fig. 4 shows a developed plate, the reduced coil part c being provided with elongated slots, f, while in Fig. 5 the elongated slots are replaced by simple perforations g which may be arranged in close proximity to one another. In this way it is possible to make the valve plate of the full thickness of metal, so that it is no longer necessary to form the coils of thinner plate than the flat plate operating the closing of the valve.

I declare that what I claim is:—

1. In a flap valve, a spindle, a spring about said spindle, a valve integral with said spring, said valve being of greater width than the part of said spring secured

110

to said spindle and a guide ring on said spindle on each side of said spring and abutting against the end of the spring.

2. In a flap valve, a spindle, a piece of sheet metal secured to and wound about said spindle, guide rings on said spindle on each side of the wound part of said sheet metal attached to said spindle, a part of said sheet metal of greater width than the part 10 of said sheet metal secured to said spindle, a portion of said wide part being arranged about said guide rings, the outer end of said sheet metal forming a valve proper.

3. In a flap valve, a spindle, guide rings 15 on said spindle, a piece of sheet metal having a narrower and a broader portion, said narrower portion being secured to and wound about said spindle between said guide rings, a portion of the wider part of said 20 sheet metal piece being also wound about said spindle, but overlapping said guide rings, the outer end of the wide portion of said sheet metal piece forming the valve proper.

25 4. In a flap valve, a spindle, guide rings on said spindle, a piece of sheet metal hav-

ing a narrower and a broader portion, said narrower portion being perforated and secured to and wound about said spindle between said guide rings, a portion of the 30 wider part of said sheet metal piece being also wound about said spindle but overlapping said guide rings, the outer end of the wide portion of said sheet metal piece forming the valve proper. 35

5. In a flap valve, a spindle, guide rings on said spindle, a piece of sheet metal having a narrower and a broader portion, said narrower portion being slotted and secured to and wound about said spindle between 40 said guide rings, a portion of the wider part of said sheet metal piece being also wound about said spindle but overlapping said guide rings, the outer end of the wide portion of said sheet metal piece forming the 45 valve proper.

In witness whereof I have hereunto set my hand in presence of two witnesses.

MAX FRIEDRICH GUTERMUTH.
